[57] CLAIM

The ornamental design for combined vacuum cleaner housing and display pedestal, as shown and described.

DESCRIPTION

FIG. 1 is a top, front and right side perspective view of a combined vacuum cleaner housing and display pedestal showing my new design;

FIG. 2 is a front elevational view thereof;

FIG. 3 is a right side elevational view thereof, the left side being a mirror image;

FIG. 4 is a top plan view thereof;

FIG. 5 is a rear elevational view thereof;

FIG. 6 is a rear elevational view of a second embodiment thereof, wherein the front and right side is the same as FIGS. 2 and 3;

FIG. 7 is a bottom plan view of the first embodiment;

FIG. 8 is a top plan view of the second embodiment; and,

FIG. 9 is a bottom plan view thereof.

The electric cord and the foot petal cord are shown broken away in FIGS. 2-9 and are understood to represent indeterminate length.

FIG. 1

FIG. 2

FIG. 3

FIG. 4

FIG. 5

FIG. 6

FIG. 7

FIG. 9

FIG. 8
